UNITED STATES PATENT OFFICE

147,364

DESIGN FOR A DISPLAY BOX OR SIMILAR ARTICLE

Robert F. Dibble, New York, N. Y., assignor to
The Royal Corporation, New York, N. Y., a corporation of New York

Application March 29, 1946, Serial No. 128,058

Term of patent 3½ years

(Cl. D80—5)

To all whom it may concern:

Be it known that I, Robert F. Dibble, a citizen of the United States of America, residing in the city, county, and State of New York, have invented a new, original, and ornamental Design for a Display Box or Similar Article, of which the following is a specification, reference being had to the accompanying drawing forming a part thereof.

Fig. 1 is a top plan view of a display box showing my new design;

Fig. 2 is a front elevation, and

Fig. 3 is an end elevation.

I claim:

The ornamental design for a display box or similar article, substantially as shown.

ROBERT F. DIBBLE.
